G. E. RUSSELL

REPAIR BOTTOM OR PLATE

Filed June 15, 1922

FIG. 1.

FIG. 2.

Inventor
G.E. Russell.

By *A. Hanafin, Jr.*
Attorney

UNITED STATES PATENT OFFICE.

GEORGE E. RUSSELL, OF HAMILTON, OHIO.

REPAIR BOTTOM OR PLATE.

Application filed June 15, 1922. Serial No. 568,656.

To all whom it may concern:

Be it known that I, GEORGE E. RUSSELL, a citizen of the United States, residing at Hamilton, in the county of Butler and State 5 of Ohio, have invented certain new and useful Improvements in a Repair Bottom or Plate; and I do hereby declare the following to be a full, clear, and exact description of the invention, such as will enable others 10 skilled in the art to which it appertains to make and use the same.

This invention relates to a repair bottom or plate.

In many containers and receptacles, for 15 instance coal buckets or scuttles, the bottom frequently wears out before the balance of the article, rendering it useless. It is the prime object of this invention to provide a repair or supplemental bottom which may be 20 used under such circumstances in order to repair the article or place it in condition for further use so that maximum use may be obtained from the same.

Another object is to provide a repair bottom or plate which may be made in a single 25 piece, stamped rapidly and expeditiously from sheet metal, and which may be readily applied to the injured bottom.

Additional objects and advantages will 30 become apparent from a consideration of the description following taken in connection with accompanying drawings illustrating one practical embodiment.

In said drawings:

35 Figure 1 is a vertical sectional view through a coal hod or scuttle repaired in accordance with my invention; and

Figure 2 is a detail perspective view of the supplemental bottom or plate.

40 Like reference characters designate like or similar parts in both views.

A conventional or representative container or receptacle is shown in the drawings by way of a coal hod or scuttle as at A. The bottom wall of said hod is designated B.

45 In use the bottom wall B frequently wears away before the side wall and remainder of the container. The invention therefore aims to provide a means whereby the bottom B 50 may be repaired or rendered serviceable for further use.

To this end a supplemental bottom in the nature of a disk or plate of any desired shape is provided as at 10. This bottom is preferably placed on top of the bottom B. Bottom 55 10 may be made from sufficiently strong bendable sheet metal and have one or more attaching spurs 11 struck therefrom and preferably pointed as at 12.

In applying the plate 10, the point 12 and lugs 11 pierce and penetrate the bottom B. The piercing may be effected by the points 12 alone or if desired holes may first be punched in the bottom B to facilitate entrance of said lugs. After the lugs have 60 passed through the bottom B, they are upset or bent and clinched against the bottom B so that the bottom 10 will be securely positioned. Thus it will be realized that the bottom consists of a single sheet or piece of 65 metal.

The supplemental or repair bottom may be readily applied by the novice as well as an experienced workman. If desired, the 70 spurs 11 may be welded to the bottom B.

As merely one practical embodiment has been illustrated and described, it is to be understood that changes in the details may be resorted to provided they fall within the 75 spirit and scope of the invention.

I claim as my invention:

1. A repair bottom for a hod or the like consisting of a plate adapted to be placed on the upper surface of the bottom of the hod, the plate having lugs struck therefrom 80 adapted to penetrate the bottom of the hod and be bent against the same.

2. The combination with a hod or the like having a bottom, of a repair bottom for the first mentioned bottom consisting of a plate 85 resting on the upper surface of the first mentioned bottom, and lugs struck from the repair bottom penetrating and secured to the first bottom.

In testimony whereof I affix my signature 90 in presence of two witnesses.

GEORGE E. RUSSELL.

Witnesses:

HERMAN L. LIST,
C. P. KRAMER.
